UNITED STATES PATENT OFFICE.

ALBERT D. WISMAR, OF BOWLING GREEN, OHIO, ASSIGNOR TO PELICAN TOY COMPANY, OF TOLEDO, OHIO, A COPARTNERSHIP CONSISTING OF ALBERT D. WISMAR AND GEORGE BLACK.

DESIGN FOR A TOY BALLOON NOVELTY.

Application filed August 8, 1927. Serial No. 23,024. Term of patent 7 years.

To all whom it may concern:

Be it known that I, ALBERT D. WISMAR, a citizen of the United States, residing at Bowling Green, in the county of Wood and State of Ohio, have invented a new, original, and ornamental Design for a Toy Balloon Novelty, of which the following is a specification, reference being had to the accompanying drawings, forming a part thereof.

In the said drawings, Fig. 1 is a perspective view, Fig. 2 is a front view, and Fig. 3 is a top plan view showing my new design.

I claim:

The ornamental design for a toy balloon novelty substantially as shown.

ALBERT D. WISMAR.
